(57) **CLAIM**

I claim the ornamental design for a mounting bracket, as shown.

DESCRIPTION

FIG. 1 is a perspective illustration of a mounting bracket according to a preferred form of the invention.

FIG. 2 is a top elevation view of the mounting bracket of FIG. 1 (with a bottom view being substantially identical).

FIG. 3 is a side view of the mounting bracket of FIG. 1.

FIG. 4 is a front view of the mounting bracket of FIG. 1, and, FIG. 5 is a rear view of the mounting bracket of FIG. 1.
